(No Model.)

T. H. SMITH.

ADJUSTABLE BRACE FOR SLAT AND WIRE AND PICKET FENCES.

No. 478,027.

Patented June 28, 1892.

UNITED STATES PATENT OFFICE.

THOMAS H. SMITH, OF OWOSSO, MICHIGAN.

ADJUSTABLE BRACE FOR SLAT AND WIRE AND PICKET FENCES.

SPECIFICATION forming part of Letters Patent No. 478,027, dated June 28, 1892.

Application filed January 16, 1892. Serial No. 418,308. (No model.)

To all whom it may concern:

Be it known that I, THOMAS H. SMITH, a citizen of the United States, and a resident of Owosso, in the county of Shiawassee and State 5 of Michigan, have invented certain new and useful Improvements in Adjustable Braces for Slat and Wire and Picket Fences; and I do declare the following to be a full, clear, and exact description of the invention, such 10 as will enable others skilled in the art to which it appertains to make and use the same, reference being had to the accompanying drawings, and to letters of reference marked thereon, which form a part of this specification.

15 Figure 1 of the drawings is a side elevation of the fence and braces, and Fig. 2 is an end view of the same.

This invention relates to certain new and useful improvements in adjustable fence 20 braces and anchors; and it consists in the novel construction and combination of parts, as hereinafter described.

In the accompanying drawings, the letter A designates a fence-section comprising the sup- 25 porting-posts B and the pickets a, the latter being held together in the usual manner by the intertwined looped wires b.

The letters C C designate the adjustable brace-wires for the picket-sections, secured 30 at their ends to the end posts and extending along the fence, crossing each other diagonally at intervals and passing through loops or eyes c on the posts and pickets. These wires are passed around tightening pins or 35 posts D, the ends of which are squared to permit the application of a crank or wrench by means of which the slack may be readily and quickly taken up.

Where a post is subjected to any extra 40 strain, as in the case of a corner or gate post, I provide an adjustable anchor therefor, which will now be described.

E designates a wire or cable, the ends of 45 which pass into the ground and are made fast to a large stone or anchor, (illustrated at F.) The intermediate portion of the wire or cable, or that portion above the ground, is formed with a V-shaped loop, and through this loop is passed a second wire or cable G, the ends 50 of which are secured to a tightening pin or peg G' in the post. By the application of a wrench or crank this pin may be turned until the post is sufficiently braced. The ends of the wire are then made fast in any suit-

able manner. If any slack subsequently occurs, the wrench may be applied and the wires or cable retightened. 55

For the purpose of keeping the posts in vertical position and to prevent their settling sidewise out of alignment truss-wires H H are 60 provided, which are secured to the upper portions of the end posts and are connected to or pass through eyes on the intermediate posts and wires extending along the fence and being crossed between each pair of adja- 65 cent posts. These wires are applied in a taut condition by means of a wire-stretcher. They may be tightened between each pair of posts by placing a block of wood between the wires and sliding it toward the point where they 70 cross.

Having described this invention, what I claim as new, and desire to secure by Letters Patent, is—

1. The combination, with a fence-post, of 75 the anchor therefor underground, the wire or cable secured thereto at its ends and having its intermediate portion above ground in the shape of a V-shaped loop, a second wire or cable secured to the post at one end, looped 80 through said V-shaped loop and back to the post, and a tightening peg or pin in the post, around which said wire passes, substantially as specified.

2. A fence or fence-section comprising the 85 supporting-posts, the pickets or slats held together by intertwined looped wires b, secured to said posts, the brace-wires C C, secured to the end posts and passing loosely through loops or eyes on the intermediate posts and 90 pickets, said wires extending along one side of the fence in opposite zigzag courses and crossing each other at intervals, the pegs or pins for tightening said wires, and the truss-braces comprising wires secured at their ends 95 to the end posts of the fence or fence-section and connected to or passing through eyes or loops in the upper portions of the intermediate posts, said wires extending horizontally above the upper ends of the pickets and in- 100 tercrossing each other between each adjacent pair of posts, substantially as specified.

In testimony whereof I affix my signature in presence of two witnesses.

THOMAS H. SMITH.

Witnesses:

E. L. BREWER,
GEORGE F. ROBINSON.
